UNITED STATES PATENT OFFICE

168,994

CAN OPENER

William E. Gundelfinger, House Springs, Mo.

Application October 3, 1952, Serial No. 21,686

Term of patent 14 years

(Cl. D22—2)

To all whom it may concern:

Be it known that I, William E. Gundelfinger, a citizen of the United States, residing in the town of House Springs, in Jefferson County, State of Missouri, have invented a new, original, and ornamental Design for a Can Opener, of which the following is a specification, reference being had to the accompanying drawing, forming a part thereof.

In the drawing:

Fig. 1 is a side elevational view of a can opener showing my new design;

Fig. 2 is a side elevational view of the opposite side shown in Fig. 1, and

Fig. 3 is a front view thereof.

The dominant feature of my design resides in the portions shown in full lines.

I claim:

The ornamental design for a can opener, substantially as shown and described.

WILLIAM E. GUNDELFINGER.
